FLORAL RACK

Charles O. Gipson, Elwood, Ind., assignor to Heinz Manufacturing Company, Inc., Elwood, Ind., a corporation of Indiana

Application September 25, 1946, Serial No. 699,229

4 Claims. (Cl. 248—27.8)

1
The present invention relates to a rack for supporting articles on the front face thereof such as floral pieces. The invention pertains to such a rack structure having means for moving the supporting prongs to extended article-supporting positions upon erection of the rack and for moving the prongs to collapsed positions when the rack is dismantled.

An object of the invention is to provide a mechanism embodied in a floral rack having a plurality of hinged prongs adapted to be automatically moved to positions extending outwardly from the front of the rack when the assembly is erected in an easel-like manner whereby floral pieces or other articles may be supported on the prongs.

A further object of the invention pertains to a floral rack embodying a means for moving the prongs to article-supporting positions upon erection of the rack in a substantially vertical position including the feature of returning the prongs to retracted positions when the rack is lifted and no longer supported on the lower ends of the bars.

A more specific object of the invention pertains to a floral rack having a plurality of bars on which prongs are mounted for pivotal movement including rods of material weight coupling the rearward ends of the prongs so as to control the hinged movement of the prongs by the action of gravity acting on the rod.

Other objects and features of the invention will be more apparent as the present disclosure proceeds and upon consideration of the accompanying drawing and the following detailed description wherein an embodiment of the invention is disclosed.

In the drawing:

Fig. 1 is a perspective view of a portion of a rack structure embodying the invention;

Fig. 2 is a longitudinal sectional view of one of the bars of the rack showing a prong thereon in the extended position; and

Fig. 3 is a similar sectional view illustrating the manner in which the prong is moved to a retracted position.

The invention is directed to a floral rack formed of a plurality of the bars 10 arranged in substantially parallel relationship and when the rack is erected for use, the bars 10 assume a substantially vertical position somewhat as illustrated in Fig. 1. The rack may include any number of bars 10 in accordance with the desired over-all dimensions desired for the rack. The rack may also be of the type which is adapted to be folded so that the bars 10 lie adjacent each

other and thereby provide a compact assembly facilitating storage and transportation of the device. The collapsing of the rack is made possible by a conventional type "lazy tongs" mechanism whereby the bars 10 are maintained in parallel relationship in the folded and in the extended positions. A portion of the "lazy tongs" mechanism is illustrated in the drawing and includes straps 11 and 12 which are connected to the bars 10 at their lower ends by means of pivot pins 14, rivets, or the like. The straps 11 and 12 are thus free to swing around the pivots 14 and the upper ends of the lazy tong straps are adapted to move lengthwise of the bars 10 during collapsing of the rack and during movement of the bars 10 away from each other. The upper ends of the straps 11 and 12 may therefore be hinged to slide members 16 which are free to move lengthwise of the bars 10. The rack may be erected in an easel-like manner by means of a rear support (not shown) so that the bars 10 then assume a position somewhat as illustrated in Fig. 1 with the lower ends 31 engaging the floor. The bars 10 are then arranged in a substantially vertical position and are maintained in substantially parallel relationship by means of the straps 11 and 12.

The bars 10 may be of any suitable cross sectional shape and in the embodiment illustrated in the drawing, each bar is provided with a groove 17 in the forward face thereof extending lengthwise of the bar. Such a bar construction facilitates the mounting of the prongs on which articles such as floral pieces are to be supported. The prongs are shown at 18 in the drawing and are mounted for pivotal movement on the bars by means of rivets, pins, or screws 21 which extend through the side flanges which form the groove 17. Any number of prongs 18 may be pivotally mounted on each bar 10, but these prongs are preferably so positioned that the "lazy tongs" mechanism does not overlie the prongs in the collapsed or folded position of the rack.

One of the characteristic features of the invention pertains to means for manipulating the prongs 18 so as to be moved automatically to the extended position shown in Fig. 2 and automatically to the collapsed position shown in Fig. 3. A rack exhibiting such means includes a rod 23 associated with each bar 10. One rod 23 is arranged rearwardly of each bar 10. Each rod 23 is pivotally connected to arms 26 which extend rearwardly from the prongs 18. The arms 26 may be welded to the rear end of the prongs 18 or formed integral therewith. In the embodiment illustrated, each arm 26 extends through

a slot 28 in the associated bar 10 immediately rearwardly of the pivot 21. The slots 28 are of sufficient length to permit swinging of the prongs 18 through at least a ninety degree angle such as from the position illustrated in Fig. 3 to the position illustrated in Fig. 2. The arms 26 may be hingedly connected to the rods 23 by means of rivets, pins, or the like as indicated at 24.

When the rack is erected for use, the lower ends 31 of the bars 10 rest upon the floor as shown in Fig. 2 and during the erection of the rack, the rods 23 also engage the floor at their lower ends whereby the rods 23 move upwardly as indicated by the arrow in Fig. 2. Such upward movement of the rods 23 swing the prongs 18 in a clockwise direction about the pivots 21 whereby the prongs 18 extend outwardly from the forward face of the bars 10 into article-supporting positions as illustrated in Fig. 1. The rods 23 may be made to have sufficient mass to maintain the prongs in the positions shown in Fig. 1 when articles such as floral pieces are supported on the prongs. In other words, the rods are heavy enough to prevent lift thereof by the lever action of the arms 26 when floral pieces are supported on the prongs 18. The slots 28 also terminate at their upper ends to form abutments limiting clockwise turning of the prongs 18 and accordingly lifting of the rods 23. The prongs 18 are accordingly moved by the rods 23 to positions for supporting floral pieces or the like and such articles are prevented from swinging rearwardly below the prongs by the bars 10 and by the straps 14 and 12 of the "lazy tongs" mechanism.

When it is desired to dismantle the rack structure, the rack may be lifted as illustrated in Fig. 3 by grasping some of the bars 10. The rods 23 are then free to move downwardly in the direction of the arrow 33 (Fig. 3) whereby the rear ends of the arms 26 move downwardly and the prongs 18 swing to positions within the grooves 17 as shown in Fig. 3. The prongs 18 are thereby moved to retracted positions automatically upon lifting of the rack. The prongs 18 are maintained in this position so long as the bars 10 are arranged in positions where the rods 23 are not urged upwardly by the action of gravity. The rack may be folded by moving the bars 10 to lie adjacent each other and this movement is made possible by the pivoted straps 14 and 12.

While the invention has been described with reference to specific structural details and with regard to a particular rack structure, it will be understood that changes may be made in the details of the members and the general organization of the assembly. Such modifications may be made without departing from the spirit and scope of the invention which pertains to weighted members for moving the prongs 18 to extend-

ed and collapsed position, as set forth in the appended claims.

I claim:

1. In a rack structure, a bar adapted to be erected in a substantially vertical position and rest at its lower end on a supporting surface, a prong pivotally mounted on said bar, and a rod connected to said prong rearwardly of the bar and of such a length as to engage said supporting surface at its lower end and swing the prong to an extended position.

2. In a floral rack, at least one bar having a groove in the forward face extending lengthwise of the bar, a plurality of prongs hinged to said bar for swinging movement into said groove, said bar having a slot therein rearwardly of each prong, an arm carried by each prong extending through the associated slot, and a rod pivotally connected to said arms and of such a length that the lower end engages the floor when the rack is erected for use so as to swing the prongs outwardly to article-supporting positions.

3. In a floral rack, at least one bar having a groove in the forward face extending lengthwise of the bar, a plurality of prongs hinged to said bar for swinging movement into said groove, said bar having a slot therein rearwardly of each prong, an arm carried by each prong extending through the associated slot, a rod pivotally connected to said arms and of such a length that the lower end engages a supporting surface for the lower end of the bar when the rack is erected for use so as to swing the prongs outwardly to article-supporting positions; and one of said slots terminating at its upper edge to provide an abutment limiting the swinging movement of the associated arm.

4. In a floral rack, at least one bar having a groove in the forward face extending lengthwise of the bar, a plurality of prongs hinged to said bar for swinging movement into said groove, said bar having a slot therein rearwardly of each prong, an arm carried by each prong extending through the associated slot, a rod pivotally connected to said arms and of such a length that the lower end engages a supporting surface for the bar when the rack is erected for use to swing the prongs outwardly from said groove whereby the rod moves downwardly when the bar is lifted to swing the prongs to retracted positions within said groove.
